UNITED STATES PATENT OFFICE.

FRANK C. LA MAR AND PETER J. HOPKINS, OF PITTSBURGH, PENNSYLVANIA.

REFILLABLE ELECTRIC FUSE.

1,318,887.

Specification of Letters Patent. Patented Oct. 14, 1919.

Application filed August 16, 1918. Serial No 250,174.

To all whom it may concern:

Be it known that we, FRANK C. LA MAR and PETER J. HOPKINS, citizens of the United States of America, residing at Pittsburgh, in the county of Allegheny and State of Pennsylvania, have invented a certain new and useful Improvement in Refillable Electric Fuses, of which the following is a full, clear, and exact description.

10 This invention relates to refillable or renewable electric fuses, wherein the fuse element or strip is inclosed in a tubular casing or shell and secured at its ends to anchoring devices fitted in or upon the ends 15 of the casing, and held in place by end caps or ferrules fitted on the ends of the casing.

The object of the invention is to provide a fuse of this type, of simple, economical 20 and efficient construction, wherein the fuse-element anchoring or supporting devices and the end caps or ferrules are securely locked in place without extraneous fastening devices, and which may readily and 25 quickly be assembled and as readily and quickly disassembled for removing a blown or disrupted fuse element and replacing it by a new one.

The invention consists in a refillable electric fuse, comprising a tubular casing, anchoring devices for supporting a fuse element in said casing having means for locking them to the casing against longitudinal movement or displacement and provided 35 with a screwthreaded member projecting therefrom, and ferrules fitted upon the ends of the casing and provided with screwthreaded openings adapted to engage the screwthreaded members projecting from the 40 anchoring devices, to thereby hold the anchoring devices in place and also securely bind the fuse element to the anchoring devices to maintain good contact therebetween, all substantially as we will proceed now more 45 particularly to set forth and finally claim.

In the accompanying drawings, illustrating the invention, in the several figures of which like parts are similarly designated, Figure 1 is a side elevation of the assembled 50 fuse. Fig. 2 is an elevation, with the end ferrules removed. Fig. 3 is a vertical longitudinal section, showing the fuse element partly in elevation. Fig. 4 is a horizontal

longitudinal section, taken substantially in the plane of line 4—4, Fig. 3, and looking in 55 the direction of the arrows. Fig. 5 is an end view of the right-hand end of Fig. 2. Fig. 6 is a section of one end of the fuse, showing a modified form of screw attachment for the anchoring devices. Fig. 7 is a section of one 60 end of a fuse, showing another form of fuse-element anchoring and supporting device. Fig. 8 is a transverse section, taken substantially in the plane of line 8—8, Fig. 7, and looking in the direction of the arrows. Fig. 65 9 is a detail view in elevation, showing a portion of another form of fuse element for use with the anchoring device shown in Figs. 7 and 8.

In the drawings, 1 represents the tubular 70 casing of insulating material, provided at its opposite ends upon diametrically opposite sides with partially circumferential recesses or cut-away portions 2, terminating in partially circumferential grooves 3.

Fitted upon the ends of the casing, are the fuse-element supporting and anchoring devices, and as shown in Figs. 2 to 5, these anchoring devices comprise disks 4, provided with slots 5 for receiving the ends of 80 the fuse element 6, and a centrally arranged screw 7, made integral with the disks, as shown in said figures, or which may be a separate screw, as shown at 8, Fig. 6, and over which the perforated end 9 of the fuse element is passed so as to contact with said disk. The disks 4 are further provided with peripheral extensions 10 adapted to fit in the cut-away portions of the casing 1, and terminate in flanges 11 adapted to enter 85 the grooves 3, whereby the disks or anchoring devices are locked on the ends of the casing against longitudinal movement.

In order to bind the ends 9 of the fuse element into good contact with the anchoring 95 disks 4, and also to confine the said disks in place upon the ends of the casing, end caps or ferrules 12, having plane or unthreaded body portions and centrally arranged screw-threaded openings 13 in their ends, are fitted 100 upon the ends of the casing, the said screw-threaded openings 13 engaging the projecting screws 7 of the disks 4, and the ferrules adapted to be rotated to draw them upon the ends of the casing over the extensions 2 105 of the anchoring devices, the inner surfaces

of the ends of the ferrules engaging the bent ends of the fuse element and holding them in good contact with the disks 4.

As herein shown, the end caps or ferrules 12 are provided with squared portions 12' to receive a wrench for turning them off in case they become too tight to be removed by hand. However, the squared portions may be omitted.

10 In Figs. 7 and 8 the invention is shown applied to another form of fuse-element anchoring device, and in this form of the device, the anchoring device is constructed similarly to the anchoring device shown in 15 Figs. 2 to 5, but instead of the disks 4 being provided with the fuse-element engaging slot, it is provided with an inwardly extending boss 14, having an outwardly tapering or conical bore 15, and fitted in said 20 boss is a fuse-element engaging clutch, comprising a radially slotted conical block 16 having a centrally arranged opening 17 to receive the end of a straight wire fuse 18, as in Fig. 7, or a flat strip fuse 19, as shown 25 in Fig. 9. The clutch block 16 is provided at its outer end with a screwthreaded projection 20 extending beyond the end of the disk, and adapted to be engaged by the screwthreaded openings in the end of the 30 caps or ferrules 12, whereby when the ferrules are turned to place upon the ends of the casing, the clutch blocks will be drawn into the tapering or conical bore of the boss 14, to thereby contract the slotted or slotted 35 end of the clutch block and securely bind the ends of the fuse element in the clutch blocks.

In order to fix the clutch blocks 16 in the boss 14 against displacement, the said clutch 40 blocks are provided with a longitudinal groove 21 extending from its inner end to within a short distance of its outer end, and a pin 22 passing through the end of the boss and projecting into the groove 21, and which 45 is adapted to engage the inner end of the groove 21 to prevent the removal of the clutch block from the boss, said pin and groove connection also serving to prevent rotation of the clutch in the boss, when the 50 end caps or ferrules are screwed to place, and thereby avoid twisting and breaking the fuse element when assembling the fuse.

In Figs. 7 and 8, the inwardly extending portions of the anchoring devices are shown 55 of less width than those in the other figures, but these parts may be constructed of any desired width around the periphery of the disks of the anchoring devices sufficient to serve the purpose of the invention.

60 In assembling the fuse, the anchoring devices are placed upon the ends of the casing and the ends of the fuse element fixed thereto as above described, and the end caps or ferrules fitted upon the ends of the casing 65 and screwed up tight, thus firmly and se-

curely binding the ends of the fuse element in contact with the anchoring devices, and thus the parts are securely locked in place against displacement by a blow-out or explosion of the fuse, without extraneous or 70 separate fastening devices, the end caps or ferrules being provided with the usual opening 23, see Fig. 4, for the escape of the gases due to a blow-out or explosion of the fuse element.

75 When the fuse is blown or disrupted, and it is desired to replace the damaged fuse element by a new one, it is simply necessary to remove the end caps or ferrules by unscrewing them and take off the anchoring devices, and the parts of the damaged fuse element may then be removed from the anchoring devices, and the fuse then renewed or refilled with a new fuse element 80 by assembling the parts as hereinbefore explained.

85 It is to be understood, that the invention is not limited to the exact details of construction herein shown and described, as the same may be changed in various particulars and still be within the scope of the appended claims, and also that the invention is not limited to its applicability to the two forms of fuse-element anchoring devices herein shown, as it is equally applicable to other well known forms of fuse-element anchoring devices.

90 What we claim is:—

1. A refillable electric fuse, comprising 100 a tubular casing of insulating material, having partial circumferential peripheral grooves near its ends, fuse-element anchoring devices fitted on the ends of the casing, each provided with an inwardly extending portion overlying the end of the casing and 105 adapted to engage the groove in the end of the casing and a screwthreaded portion projecting from the outer face thereof, and ferrules having plane or unthreaded body portions and adapted to be fitted upon the 110 ends of the casing over the inwardly extending portions of the anchoring devices and provided with screwthreaded openings in their end walls adapted to engage the screwthreaded projections on the fuse-element anchoring devices for locking the parts 115 in place.

2. A refillable electric fuse, comprising 120 a tubular casing of insulating material, having cut-away portions at its ends terminating in circumferential grooves, fuse-element anchoring devices fitted on the ends of the casing and provided with inwardly extending portions fitting in said cut-away portions of the casing, and terminating in inwardly projecting flanges entering the circumferential grooves in the casing, and screw-threaded members projecting from the outer faces of the fuse-element anchoring devices, and ferrules adapted to fit upon 125

the ends of the casing over the flanged inwardly extending portions of the fuse-element anchoring devices and provided with screw-threaded openings in their ends 5 adapted to engage the screwthreaded projections on the anchoring devices for locking the parts in place.

In testimony whereof, we have hereunto

set our hands this 13th day of August 1918,
at Pittsburgh, Pa.

FRANK C. LA MAR.
